CUTLERY HOLDER FOR SILVERWARE CHESTS

William R. Vermillion, Kansas City, Mo.

Application August 9, 1948, Serial No. 43,276

2 Claims. (Cl. 206—16)

1

The present invention relates to chests or containers for articles such as cutlery or silverware or the like, and aims to provide a novel supporting or holding means for the cutlery articles forming part of such cutlery sets or collections.

Accordingly a primary purpose of the invention is to provide a chest or receptacle having a movable cutlery rack or support which is adapted, in one of its positions, to permit ready removal or replacement of the cutlery pieces, and in another position of said rack or support to prevent any such removal of the cutlery articles and also to prevent any casual displacement of the rack or support from the latter position.

For accomplishing this purpose, I provide a chest or receptacle having a hinged cover or lid in which is accommodated the movable rack or support, which is adapted to be collapsed within the cover for retaining the cutlery articles in stored position, and held in such collapsed condition against any casual displacement regardless of the open or closed relation of the cover; whereas on opening of the cover the rack may be released and shifted slightly outwardly into position for permitting removal or replacement of the cutlery articles.

In this connection it is also an object of the invention to provide a construction of the character described in which the cutlery articles themselves cooperate with the lid or cover and holding rack or support in preventing any casual movement of the latter from its inwardly collapsed condition inside the cover.

It is also sought to provide an extremely simple as well as practical construction for carrying out the desired objects of the invention, and of such form as to be readily and economically constructed, and likewise easily and conveniently operated.

With the foregoing general objects in view, as well as minor objects as will appear in the course of the detail specification, the invention will now be described by reference to the accompanying drawing illustrating one form of construction which I have devised and found to be both practical and efficient, after which those features and combinations deemed to be novel and patentable will be particularly set forth and claimed.

In the drawing:

Figure 1 is a perspective view showing an open cutlery receptacle such as a silverware chest having its lid or cover equipped with a rack or holder structure embodying the present invention;

Figure 2 is a sectional view, on a larger scale and representing a section taken on the line 2—2 of Figure 1, for showing one of the guide slots provided in the lid or cover member for cooperating with said rack or holder structure;

2

Figure 3 is a similar sectional view, representing a section taken on the line 3—3 of Figure 1, and showing the rack or holder structure in its inwardly collapsed condition;

5 Figure 4 is a similar sectional view representing said rack or holder structure in released and outwardly extending position to permit manipulation of the cutlery articles, as indicated by the dotted lines in said view; and

10 Figure 5 is a detail sectional view representing a section taken on the section line 5—5 of Figure 3.

Referring now to the accompanying drawing in detail, the improved construction is illustrated 15 as arranged in interior relation to a cutlery receptacle such as a silverware chest or container, comprising a main section 10 and also a lid or cover section 12 connected by hinges 14 to the upper rear margin of the main section 10, which latter is provided with the usual partition bar 16 20 formed with vertical slots or recesses 18 for receiving the forks, spoons, etc. designed to be placed in the container.

For supporting the remaining pieces of the set 25 of cutlery to be placed in the container, such as knives 20, a rack frame or folder is provided, which is movably supported inside the lid or cover member 12. This rack frame or holder is of rectangular shape and comprises an upper bar 22 and a lower bar 24 which are connected at their ends by means of a pair of spacing rods 26 whereby said bars are held in spaced and parallel relation and with some provision for slight upward and downward movement of the frame 30 within said cover member.

The upper and lower ends of said rack frame are provided, at each corner thereof, with outwardly projecting pins 28 for engagement with guide slots 30 formed in the opposite sides of the cover member 12. As clearly illustrated in Figure 2, the lower end of each of the slots 30 (adjacent to the hinged margin of the cover) is formed with a bypass 31 communicating with a drop extension of the slot passage, as indicated at 32, and adapted to permit an outward swinging 40 of the lower portion of the rack frame and also a lowering of the same from the position shown in Figures 1 and 3 into the position illustrated in Figure 4 of the drawing, for a purpose 45 presently to be described.

50 The upper bar 22 of the rack frame is provided with openings 34 for the passage of the upper ends of the knives 20, the lower ends of which are adapted to be received in sockets or pocket form of recesses 36 provided in the lower bar member 24 in vertical alinement with said openings 34 of the upper bar—as shown in Figures 1 and 3, the arrangement being such that the knives may be inserted upwardly through the 55 openings 34 and then dropped for inserting the 60 openings 34 and then dropped for inserting the

lower ends of the knives into said sockets or pockets 36. For either inserting or removing the knives, the rack frame is swung outwardly and dropped into the position illustrated in Figure 4, the lower pins 28 passing through the bypasses 31 and thence into the drop extensions 32 for permitting lowering of the rack frame into the position shown in Figure 4. In this position of said frame, the knives may be lifted to disengage their lower ends from the sockets 36 and then removed by withdrawal of their upper ends from the openings 34—as represented by the dotted lines in Figure 4.

The operation of inserting the knives into the supported position illustrated in Figures 1 and 3 is carried out in just the reverse manner, after which the rack frame is swung back into the cover member and dropped for engagement of the lower pins 28 with the lower ends of the vertical slots 30. In this position the upper ends of the knives are designed to act as stops adapted to engage the adjacent inner face of the cover member and thereby limit any casual movement of the rack frame which would tend to permit outward swinging movement of the lower pins 28 through the bypass openings 31 and into the drop extensions 32. Obviously the guide slots 30 can be extended downwardly or shortened for accommodating whatever length of knives are to be mounted in the rack frame; and it is moreover pointed out that the design of the lower ends of said slots 30 includes a slight forward swell or enlargement 38 adapted to seat the pins 28 as the rack frame settles into parallel relation with the adjacent main portion of the cover member, as represented in Figure 2. This construction incidentally provides a hump portion or shoulder 39 at the mouth of each bypass 31 adapted to counteract any such casual movement of the lower pins 28 as would be sufficient to allow the same to move into said bypass openings and hence permit outward swinging movement of the rack frame into the position illustrated in Figure 4.

It will therefore be apparent that when the knife pieces have been duly assembled in the rack frame and the latter collapsed into the cover member in the relation illustrated in Figures 1 and 3, the cover member may be closed with relation to the main body or storage section 10, and subjected to any ordinary handling without any likelihood of the articles supported by the rack frame becoming disengaged from their supported position.

For facilitating the insertion of the rack frame into proper operative position within the cover member or the complete removal of the same from the cover member, when necessary, the drop extension passages 32 may be provided with outlet openings 40 at their upper ends (or above the bypass connections 31), as clearly shown in Figures 2 and 3, thus allowing the pins 28 to be completely disengaged from the lid or cover member.

Moreover, as a feature for insuring against any possibility of the rack frame shifting materially out of the position illustrated in Figures 1 and 3, I prefer to provide a small and simple latching device such as a button element 42, in one corner of the lid or cover member 12, being frictionally mounted on a pin or screw 44 so as to be turned either inwardly across the upper end of the adjacent slot 30 or outwardly into the position shown in Figures 2 and 4, that is, entirely out

of the path of the rack frame's movement. Thus in its inner or latching position (as represented in Figure 3) said button element 42 is directly in the path of movement of said rack frame so as to positively prevent any movement thereof sufficient to allow the lower pins 28 to come up opposite the bypass openings 31 regardless of the position of the lid or cover member; but turning of the button 42 outwardly into the position shown in Figures 2 and 4 will then allow the deliberate movement of the rack member for the release and further manipulation of the same—as has been above described.

It will thus be seen that a practical and efficient as well as economical construction has been devised for fulfilling all the desired objects of the invention as aforesaid; and while I have illustrated and described what I now regard as the preferred form of embodiment of the proposed improvements, I nevertheless desire to be understood as expressly reserving the right to make whatever changes or modifications may fairly be deemed to fall within the spirit and scope of my invention as defined by the appended claims.

Having thus described my invention, what I claim and desire to secure by Letters Patent is:

1. A receptacle for cutlery and the like comprising, a main storage section, a lid or cover member hingedly connected with said main storage section, and having the opposite sides thereof formed with interior guiding slots, a rack member for supporting a plurality of cutlery articles and provided with pins for engagement with said guide slots, the lower ends of said guide slots having outer drop extensions for permitting a lowering of said rack member and also an outward shifting of the lower portion thereof away from the interior of the cover member.

2. A receptacle for cutlery and the like comprising, a main storage section, a lid or cover member hingedly connected with said main storage section and having the opposite sides thereof formed with interior guide slots extending parallel with the main interior face of said cover member, a rack member for supporting a set of cutlery articles and provided with upper and lower guide pins for engagement with said guide slots and the lower ends of said slots being adapted to set the lower pins of the rack member with the latter substantially parallel with said interior face of the cover member, said lower ends of the slots being also formed with shoulders adapted to prevent casual upward movement of the pins and also having outer drop extensions for permitting a lowering of the rack member and an outward shifting of the lower portion thereof away from the interior of the cover member.

WILLIAM R. VERMILLION.
